ONE WHEELED SKATE
Robert E. Pierce, 11189 Royal Palm,
Arlington, Calif. 92505
Filed June 1, 1965, Ser. No. 460,102
17 Claims. (Cl. 280—11.24)

This invention relates to a vehicular device, and particularly to such a device primarily suitable for play use by children.

The vehicular device of this invention comprises a pair of unique, wheeled members of similar construction but configured in mirror image relationship to each other. Thus, it is actually two devices, rather than one, being, in this respect, like a pair of roller skates. This makes for some difficulty of description since, to be literally correct, the vehicular device should be referred to in plural terms. However, for purposes of simplicity, grammatical purity will hereinafter be sacrificed to ease and clarity of expression and, consistently therewith, the invention will be referred to in the singular as a vehicular device or the equivalent, as by use of the expression "vehicle," "vehicular toy" or simply "toy."

Turning now from grammatical form to the substance of the invention, my vehicular toy moves, as will be seen, by means of ground contacting wheels but, also as will be seen, similarity to the toy to conventional wheeled vehicles here ceases. The toy is uniquely different, from both structural and use standpoints, from any conventionally known type of child's vehicle. Being thus different, it captures the child's interest and imagination and presents him with a new challenge to his natural skills and athletic abilities. My vehicular toy is, by the unusual nature of its use, capable of providing a child or young person of almost any age, or, in fact, any healthy adult, with many hours of fun and pleasure. It is suitable for use by a child playing alone or in the company of others, and it lends itself well to competitive activities by providing the participants with an opportunity to match their balancing and other skills; co-ordination; strength; and endurance against each other.

It is thus a principal object of this invention to provide an exotically different type of vehicular toy to capture the imagination of children and present them with a challenge to their skills and athletic abilities.

It is another object of the invention to furnish such a toy capable of providing its use with many hours of fun and pleasure.

It is still another object of the invention to furnish such a vehicular toy capable of providing children with healthful fresh air exercise while, at the same time, affording them pleasure.

It is yet another object of the invention to furnish such a toy susceptible to relatively quick mastery of use by any child of ordinary athletic ability yet so characterized as to provide the most athletically gifted child with a continuing challenge to his expertise.

It is still another object of the invention to furnish such a vehicular toy capable of bringing about improvement of its user's balance, coordination, strength and endurance upon continued use thereof.

Other objects, features and advantages of my vehicular toy will become apparent from the following description, considered in conjunction with the accompanying drawing, of which:

FIGURE 1 is a side view of a boy riding a preferred embodiment of the vehicular toy and illustrating the above-indicated paired-member character thereof.

FIGURE 2 is an enlarged side elevation of one of the two paired members of the FIGURE 1 embodiment of the toy.

2

FIGURE 3 is a front elevation of the FIGURE 2 member.

FIGURE 4 is a top view of the FIGURE 2 member.

FIGURE 5 is an enlarged view, mostly in section, through an important structural part of the member, showing dual-function means for adjusting its height and holding separate parts thereof together, taken along line 5—5 of FIGURE 2.

FIGURE 6 is an enlarged fragmentary view, mostly in longitudinal section, of an important feature of the pictured member, taken along line 6—6 of FIGURE 3.

FIGURE 7 is a still further enlarged view, mostly in cross section, of the FIGURE 6 feature of said member, taken along line 7—7 of the latter figure.

Turning now to consideration of the drawing in greater detail, there is shown in FIGURE 1 a pair 1 of wheeled members comprising a preferred embodiment of my vehicular toy being ridden by a child to illustrate the manner in which the toy is mounted and handled by its rider. As that figure shows, the toy is ridden in standing position with the lower arms and feet separately supported by means, and in a manner, hereinafter described, and each of the hands gripping a separate one of a pair of handgrips provided for that purpose. The handgrips are shown at 9 and 10, the former being for the use of the right hand, and hereinafter referred to as handgrip 9, and the latter being, of course, for the use of the left hand.

While a small portion of one of the wheeled members is hidden behind the rider in FIGURE 1, this does not detract from the completely illustrative character of that view relative to the use of my vehicular toy. In this connection, it is sufficient to say that the pair 1 of wheeled members comprises a left and a right member, the former designed to support the rider's left arm and foot, and having a handgrip for his left hand, and a latter having the same function and relationship relative to his right arm, foot and hand, respectively. The two members can thus be referred to as left and right members. The former will be hereinafter designated by the reference character 1a, and the latter by the character 1b.

Left and right members 1a and 1b, respectively, of pair 1 are, as previously indicated, mirror image twins, thereby differing from each other in ways dictated by their mirror image relationship in the same way that one of a pair of shoes differs from the other. The points of mirror image-induced dissimilarity between the two members will be readily apparent from the drawing and its present description. Because of their otherwise similarity of construction and use, only the right one (1b) of the pair 1 of said members is illustrated in detail in the applicable figures of the drawing. Consequently, the bulk of the drawing description to follow will be concerned primarily with member 1b and its component parts, as shown in FIGURES 2 through 7.

Because of the relative simplicity of my vehicle, from both structural and use standpoints, and the substantial structural similarity of its two members, as evidenced by the FIGURE 1 illustration, the here adopted method of describing the invention in terms of reference primarily to one of its members is considered completely adequate for the purpose. Even though such is unnecessary for an adequate teaching of the present invention, care will, nevertheless, be taken hereinafter to point out the areas of mirror image dissimilarity between members 1b and 1a, so that the description will, in effect, constitute a teaching of the structural configuration of the latter, as well as of the former.

Member 1b comprises an upper tubular part 3, serving essentially as an arm support and handle bar for the rider to grip with his right hand, and a lower part, or chassis

5, consisting primarily of a rotatably mounted wheel 13 which contacts the ground in rolling relationship, a bent tubular member 6 which serves as a support frame for chassis 5 (hereinafter referred to as chassis frame 6), and a footrest 15 fixedly secured to chassis frame 6 in suitable positional orientation to accommodate the rider's right foot. The relative sizes and configurations of the various parts of chassis 5, and the manner in which they are assembled to form the complete chassis, are well illustrated by the drawing.

Wheel 13 is of the spoked type with a rim on which a tire 16, which can be of either the solid rubber or balloon variety, is mounted. The wheel can, if desired, be of the disc, rather than spoked, type and it can be of any size suitable for the intended purpose, but, as presently contemplated, is preferably about 8 or 10 inches in diameter. Chassis frame 6 is bent through two right angle turns to form an axially monoplanar member of squared Z-shape, having a first leg 6a adapted to depend downwardly and serve as a bracket for an axle 17 around which wheel 13, as will be seen, rotates; a second leg 6b adapted to extend upwardly and meet the lower end of upper part 3 of member 1b in a manner and for a purpose subsequently explained; and an intermediate transverse section 6c integrally connecting legs 6a and 6b and providing a support base for footrest 15 which is affixed thereto in the manner illustrated in the drawing and discussed hereinafter.

Chassis frame 6 is, as previously noted, of tubular construction. However, the lower end of its depending leg 6a is plugged with a tight fitting metal insert 19 weldably attached around the edge of its lower end to the surrounding rim of the lower end of leg 6a, as FIGURE 3 illustrates. Depending leg 6a and metal insert 19 have aligned openings forming a central passageway running through the leg perpendicularly to its axis. The passageway is so sized and configured as to receive and snugly hold one end of axle 17 in tight friction fitting relationship. Axle 17 has a slightly flattened head 17a, the presence of which prevents migration of the axle through the aforesaid passageway in the direction of rotating wheel 13 (which, as will be seen, is disposed on the opposite side of chassis frame leg 6a therefrom) during operation of the vehicle. The passageway is so directionally oriented relative to depending leg 6a of chassis frame 6 as to position the axle, when seated therein, parallel to transverse section 6c of said frame. The interfit orientation of axle 17 and depending leg 6a of the chassis frame is illustrated particularly well in FIGURE 3.

As will be clear from FIGURE 3, axle 17 is so seated in the aforesaid passageway through depending leg 6a of chassis frame 6 as to bring its flattened head 17a against that surface of the leg which is turned diametrically away from the direction of extension of transverse section 6c of the frame therefrom. This results in projection of the wheel 13 engaging section of the axle from leg 6a in such direction as to position it underneath, and, as previously indicated, parallel to, transverse frame section 6c. Wheel 13 is mounted on the thus projecting portion of axle 17, as a result of which it is aligned planarly parallel with leg 6a and perpendicular with the transverse section of the chassis frame. The length of leg 6a is sufficient to provide ample clearance between the top of wheel 13 and said transverse section and thus permit free turning of the wheel relative thereto. The presence of insert 19 in the leg 6a of the chassis frame assures better axle retention by its passageway seat in the leg and increased strength of the resulting axle-leg connection.

Wheel 13 is rotatably mounted on axle 17 by means of a hub comprising an ordinary ball bearing having an inner race friction-fitted on the axle and an outer race coactively associated with the wheel whereby the latter is permitted to rotate around the relatively stationary axle as it rolls along the ground to thereby move the

vehicle and transport its rider. The ball bearing mounting is not specifically shown in the drawing since such mountings are commonly known to those skilled in the art. While the friction fit between the inner race of the ball bearing and axle 17 tends to hold the wheel in its proper axial orientation on the axle, and the tight fit between axle 17 and its passageway seat in leg 6a tends to keep the axle properly oriented during operation of the vehicle, a shim washer 21 is positioned on the axle intermediate the wheel and leg 6a, and a cotter pin 23 is locked in place through a mating hole in the outer extremity of the axle adjacent the outer hub of the wheel to obviate the possibility of undue migration of the involved parts during operation of the vehicle. Such migration is undesirable in that it could cause wheel malfunctioning or loss or bring the wheel into rubbing contact with leg 6a.

The term "ground" as employed herein to indicate the surface on which wheel 13 rolls to achieve movement 20 of the vehicular toy is intended to have a broad meaning. More specifically, that term is here employed to denote any sufficiently hard surface of operation for the toy such as, for example, a paved street, sidewalk, hard clay, lawn, or the like, surface. As in the case of other rolling 25 vehicular toys, the preferred outdoor surfaces of use for the present vehicle are hard pavements such as concrete, blacktop, etc., pavements. The device is not limited to outdoor use, however, and is readily adaptable for riding in large buildings, or other structures, on floors of any 30 description, so long as they are adequately smooth for the purpose.

Footrest 15 is a flat, elongated piece of plate metal, 35 of sufficient length and width to accommodate a child's, or young person's, foot with room to spare when the vehicle is in use, or positioned for use as shown in the drawing. The footrest has two transversely central slots 15a and 15b, respectively, positioned in line and symmetrically distributed either side of its transverse bisector. The slots completely penetrate the footrest and serve a 40 purpose hereinafter explained. As indicated above, footrest 15 is fastened atop transverse section 6c of the chassis frame, the fastening being accomplished by weld means as illustrated in FIGURES 4 and 6. The footrest is so positioned, relative to the chassis frame, as to orient it 45 horizontally when member 1b is in its upright position, as shown in the drawing. Footrest 15 is laterally spaced on transverse section 6c of the chassis frame so as to align its longitudinal bisector with the centerline of the tread of tire 16. This spacing arrangement positions the 50 right foot of the rider directly over wheel 13 when he is riding the vehicle.

The upper surface of footrest 15 is preferably, either 55 entirely or partially, of a non-skid character or texture. This can be accomplished by corrugating, or otherwise roughing, the upper metal surface of the footrest itself, or by fastening a layer of rough textured material thereto. The various methods for rendering metallic surfaces non-skid, or applying non-skid overlay materials to existing surfaces, are so well known as to require no discussion here. Where only part of the upper surface of the footrest is to be of non-skid character, that part will 60 preferably comprise the central portion, as exemplified by the surface area within the continuous dotted line of FIGURE 4, since it is here that the rider will stand when 65 operating the vehicle.

To aid the rider in keeping his footing on the vehicle, 70 a pair of complementary footgrips 25 and 27 are provided for use accessory to the footrest. The two footgrips are similar but not interchangeable, footgrip 25 being adapted to fit the left side of the foot, and footgrip 27 its right side. As the drawing shows, the footgrips are almost, but not quite, mirror image twins. The structural difference 75 by which they miss being such twins is so slight as to go almost unnoticed. The character of, and reason for, this difference will later be discussed in detail. Each of the

footgrips comprises an elongated piece of plate metal, flat for a good portion of its length then bent sharply upwardly and curvingly over its flat portion to form a half-arch of forwardly converging configuration. The thus arched portion of footgrip 25, hereinafter referred to as half-arch 25a, is formed sufficiently higher than its counterpart portion of footgrip 27, hereinafter called half-arch 27a, to compensate for the thickness of the plate metal from which both footgrips are made. The purpose of this difference in arch height, which is the structural difference of above reference, is to permit assembly of the two footgrip members for use with their flat segments in underlying-overlying relationship, as subsequently discussed in greater detail, and, at the same time, assure curvature of their half-arches toward each other along the common arcuate pattern illustrated in the drawing, and particularly FIGURE 7.

As the drawings show, and will be apparent from the foregoing remarks, the flat portion of each of the footgrips is elongated, the reason for which will become evident as the description of the invention proceeds. Each of the two flat portions has a transversely and longitudinally centered slot running for a good portion of its length. The two slots are shown on the drawings at 25a (in footgrip 25) and 27a (in footgrip 27), and will be hereinafter so identified. The slots extend completely through the footgrips and are so positioned as to overlap for most of their lengths when the foot-grips are secured to the vehicle for use in the below-described manner.

The two footgrips are installed for use on footrest 15, this being accomplished by bringing their flat sections underneath the forward, or right, as seen in FIGURE 4, end of the footrest, with that of footgrip 27 overlying the other. The footgrips are oriented, for this assembly procedure, with their half-arches extending upwardly and converging forwardly and with their flat portions in transverse edge coincidence. The two footgrips, thus positionally oriented, are fastened in place on the footrest with the upper surface of the flat portion of footgrip 27 flush against the under surface of said footrest, by means of a machine screw 29 secured with a nut 31, as shown in FIGURE 7. Screw 29 has an oval head of diameter sufficiently larger than the width of slot 15b in the footrest to prevent its passage therethrough and provide the screw with support means on the foot-rest when it is locked in place. As the drawings show, the head of screw 29 is positioned within the normal tread area of footrest 15, and it is to minimize foot discomfort to the rider of the vehicle that it is of the oval head type. Other screw head arrangements, some offering even less discomfort to the vehicle rider, can, of course, be employed within the scope of my invention. As an example of one such alternative arrangement, the screw head can be countersunk, in any of a variety of ways known to those skilled in the art, so that it does not protrude from the upper surface of the footrest.

Returning now to the footgrip fastening arrangement of the picture vehicle, the drawings clearly show that this is accomplished by passage of screw 29 through slot 15b of the footrest and underlying slots 27b and 25b of footgrips 27 and 25, respectively, which by virtue of the previously mentioned lateral edge coincidence of their flat portions are in alignment for most of their lengths. The screw is, as previously indicated, positioned with its threaded end down and its head supported on the edges of slot 15b of the footrest. The screw is of sufficient length to project far enough below the surface of the flat portion of footgrip 25 to receive nut 31 on its threaded end. A washer 33 having a diameter substantially greater than the width of the slot in footgrip 25 is fitted on screw 29 between the footgrip and nut 31 to provide a firm flat base against which the nut can be tightened.

The drawings, and particularly FIGURES 3, 4 and 7, show footgrips 25 and 27 fastened to footrest 15 with their upstanding half-arch portions snugged tightly at their bases against the lateral edges of footrest 15 and this is

the preferred arrangement where the footrest is fairly wide, since a rider's foot of almost any size is thereby accommodated. The method of foot accommodation will be clear from the drawings, and especially FIGURE 1, but, briefly, the two footgrips, when assembled on the footrest in the manner described and illustrated herein, form a stirrup-like toe socket or guard into which the rider's foot fits. The reason for assembling the footgrips with their half-arches forwardly converging is obvious since this orientation more nearly fits the contours of the human foot than would the reverse (forwardly diverging) half-arch orientation.

An important advantage, not heretofore noted, of my particular footgrip arrangement resides in a size adjustment capability, made possible by the slotted configurations of the footgrips and footrest, whereby it can be quickly adjusted to accommodate the foot size of any rider. The footgrip arrangement is adjustable width-wise, length-wise or both, the width adjustment being accomplished by lateral shift, relative to foot-rest 15, of the footgrip members, and the length adjustment by longitudinal shift of the pair of footgrips along the footrest.

The lateral shift of the footgrips for width adjustment is of greater importance on vehicles with narrower footrests than those of the drawing embodiment of my invention, since the footrests of the latter are sufficiently wide to accommodate a foot of almost any size, even with the footgrips snugged close to their lateral edges as shown and described. Carrying out such a lateral shift is made possible by the heretofore disclosed relationship of superimposition between slot 27b of footgrip 27 and slot 25b of footgrip 25 which makes movement of either footgrip outwardly from its FIGURE 7 position, and then inwardly an equivalent distance, possible, upon loosening of the screw 29 and nut 31 locking arrangement.

The longitudinal shift of the footgrips along footrest 15 is of even greater simplicity than their lateral shifting since all this requires is movement of loosened screw 29, and the footgrip assembly held together thereby, fore and aft, as necessary, in slot 15b of the footrest.

As previously noted, and illustrated on the drawing, footrest 15 has a slot 15a similar in all respects to slot 15b but situated in its half-section opposite that of the latter slot. Slot 15a serves footgrip anchoring and longitudinal shaft purposes equivalent to those served by slot 15b, but for the benefit of the rider's left, rather than his right, foot. This left-right versatility of the foot support assembly of the pictured embodiment of my invention will be explained, and discussed, in greater detail below. Insofar as the structural, functional and use aspects of the assembly are concerned, however, enough has been said for a full and adequate teaching thereof.

The only part of lower part 5 of member 1b not yet discussed in detail is upwardly extending leg 6b of chassis frame 6. Leg 6b serves as a socket for a round, solid metal rod 35, which is inserted to the depth indicated in FIGURES 2 and 3 which show the rod in dotted outline form, and weldably secured in place therein. Rod 35 serves to link upper and lower parts 3 and 5, respectively, of member 1b and hold those parts together. In the latter connection, rod 35 has a plurality of evenly spaced holes 35a running transversely, centrally and from front to back therethrough, all of the holes being disposed in that portion of the rod protruding upwardly out of leg 6b of chassis frame 6. The manner in which these holes are utilized for the indicated purpose of holding the parts of member 1b together will shortly be explained.

Upper part 3 of member 1b consists of an elongated metal tubing member 4 bent to suitable shape for multiple purposes, as subsequently outlined, and having hand and arm grips 9 and 11, respectively, joined thereto. Metal tubing member 4 has, as the drawing shows, a downwardly depending leg 4e forming its bottom section; a section 4a extending forwardly and upwardly from a bend joining it to the upper end of leg 4e; a short upright

section 4b extending vertically upwardly from a shallow bend joining it to section 4a; a handle bar section 4c extending downwardly, rearwardly and slightly outwardly (relative to the rider's position) from a sharply curving bend joining it to section 4b; and an armrest section 4d extending rearwardly, slightly upwardly and slightly outwardly (again relative to the rider's position) from a bend joining it to handle bar section 4c. Tubular member 4 has a round cross section of the same diameter as that of chassis frame 6.

As previously indicated, bar 35 serves to link upper and lower parts 3 and 5, respectively, of member 1b. To accomplish this, the bar is so sized and positioned as to fit telescopically within leg 6b of chassis frame 6 at its (the bar's) lower end, to the depth indicated above, and into downwardly depending leg 4e of tubular member 4 for that part of its length protruding upwardly out of said leg 6b. The telescopic fit between bar 35 and leg 6b of chassis frame 6 is nonbinding but sufficiently snug to vertically align the bar when the chassis frame is in the upright position shown in the drawing. Tubular member 4 is hollow throughout its length and open at the bottom end of its downwardly extending leg 4e, thus permitting that leg to downwardly telescope around that portion of rod 35 which projects upwardly from the up-standing leg of chassis frame 6.

The upper end of leg 6b of chassis frame 6 and the bottom of downwardly extending leg 4e of tubular member 4 are square cut, and the length of bar 35 is such as to terminate at its upper end just short of the bend between downwardly extending leg 4e and forwardly bending section 4a of tubular member 4, whereby the telescoping of its leg 4e in the above-indicated manner permits member 4 to slide downwardly along the rod until its lower end abuts against the upper end of leg 6b of chassis frame 6. By virtue of these features of member 1b, its upper and lower parts are fitted together, rod 35 being sufficiently long to stiffen the framework of the vehicle member at the juncture of said parts and of sufficient cross sectional size to assure a snug and substantially wobble-free fit at that juncture.

Downwardly extending leg 4e of tubular member 4 has a plurality of pairs of diametrically opposite openings 4ea so spaced thereon, and so mutually aligned, as to coincide with the above-mentioned holes 35a in rod 35 when upper part 3 is in its proper rotational position, relative to the lower parts of the vehicle, on rod 35. The upper and lower parts of vehicular member 1b are locked together by aligning the holes in rod 35 and downwardly extending leg 4e of tubular member 4 and then passing a toggle pin 37 through one of the sets of aligned holes, as shown on the drawing, and particularly FIGURES 2 and 5. The fit of the toggle pin within the aligned holes in the rod and tubular member walls is snug to assure a more stable and wobble-free connection, but substantially non-binding so that the pin can be fairly easily moved from one set of aligned holes to another for purposes of vehicle height adjustment.

Toggle pin 37 is of a conventional type, with a head 37a at one end to prevent migration of that end through the openings in the parts of the vehicle held together thereby, and a pivoted member 37b at its other end adjustable to an open position in which it is aligned with the main portion of the toggle pin for insertion through said openings, and a locked position, as shown in the drawing, to which it is adjusted after insertion through the openings to hold it in place and thereby prevent separation of the upper and lower parts of vehicular member 1b. Such toggle pins, and their manner of operation, are well known in the art and need no further description here.

Tubular member 4 owes its unusual shape to its multi-functional character as an arm support, handle bar and structural member serving to hold the various parts of

member 1b together. Thus, the depending leg section 4e of tubular member 4 helps connect upper part 3 with lower part 5 of member 1b; handle bar section 4c of the tubular member is positioned and oriented where it can be easily grasped by the right hand of the rider of the vehicle, and thereafter used by him as a guide member; arm support section 4d is directionally oriented to underlyingly parallel the right forearm of a rider gripping handle bar section 4c; and the remaining parts of the tubular member are so sized, shaped and integrally positioned as to join the other parts of the member into a cohesive whole.

As previously indicated, arm support section 4d mostly underlies the right arm of the rider operating the vehicle. Section 4d is augmented in its arm support function by an upturned arm grip member 11 of U-shaped cross section, fixedly secured atop, and near the aft end of that section of the tubular member by welding means, as shown. Arm grip member 11 has two upstanding side sections and a horizontally disposed bottom section, 11b, 11c and 11d, respectively, all of which are disposed parallel to said section 4d. Additionally, the upstanding side sections of arm grip member 11 are disposed equidistantly from the vertical, longitudinal bisector of section 4d.

Thus configured and positioned, arm grip member 11 cradles the upper forearm of the rider of the vehicle when member 1b is properly adjusted for height by means of the above-described telescoping and locking arrangement between rod 35 and leg 4e of tubular member 4. As indicated above, and illustrated in the drawing, arm grip member 11 has vertically upright side sections. Curved side sections, more nearly conforming to the shape of the human arm, could, however, be employed if desired. It might even be preferable in some, or even most, instances to so shape the side sections of the arm grip member that they curve, or diverge, inwardly toward each other, at least at their tops, to permit the arm grip to clamp the rider's arm to some extent rather than merely cradling it. Arm grip member 11 is lined with a suitably resilient shock absorbing material 12 such as sponge rubber, foamed plastic, or the like.

Handle bar section 4c of tubular member 4 is sleeved by a handgrip 9, previously referred to but not by reference character, of a suitably yielding material such as rubber, plastic, or the equivalent. The purpose of the handgrip is so obvious, and handgrip designs, materials of construction, etc., so well known, as to require no additional discussion here. Before leaving the physical description of the pictured embodiment of my invention, and particularly tubular member 4 and its appurtenant parts, it should be noted that all directionally definitive language heretofore employed (such as language indicating a particular part to be downwardly depending, outwardly extending, etc.) is referable to the upright position of member 1b as illustrated on the drawing.

The various parts of my new vehicle can, of course, be metallic or made of any other suitable material or materials. As a matter of preference, however, the vehicle should be of light weight, such as, for example, substantially aluminum, construction.

As previously indicated, lower part 5 of member 1b of the pictured embodiment of my vehicle is so designed as to be equally serviceable as the corresponding lower part of left member 1a of the vehicle. Thus, at least insofar as their lower parts are concerned, the left and right members of the vehicle are interchangeable duplicates, the advantages of which, from both manufacturing and use standpoints, are too obvious to require further comment. To switch the lower part of left or right member 1a or 1b of the vehicle to serviceability as the lower part of the other member, it is merely necessary to move the two footgrips from one end of the footrest to the other, the manner of doing this and the use ramifications thereof being obvious from an understanding of the manner of construction and operation of my new vehicle as

made clear by the attached drawing and its detailed description above.

The manner in which my new vehicle is ridden will, it is believed, be fairly apparent from the drawing and particularly FIGURE 1, which actually shows a rider in operating position thereon. Briefly, the rider positions himself for vehicle operation by placing his feet on the appropriate ones of the footrests of the left and right vehicle members (corresponding to members 1a and 1b, respectively, of the drawing) and appropriately grasping the left and right handgrips, with his forearms cradled in their cooperating arm grip members, all as clearly demonstrated in FIGURE 1. Thus positioned, the rider propels himself along the ground by leg motion somewhat analogous to a skater's leg movements but, at the same time, he guides and supports himself by arm and hand movements transmitting their influence and control at the arm grip and handle bar points of contact between rider and vehicle. The skill, balance, coordination, etc., required to master control of my new vehicle will, it is believed, be appreciated by anyone who has ever learned to ride any of the conventional vehicles requiring skill and balance such as bicycles, roller skates, ice skates, etc.

By skater's leg movements, as the term is employed in that, or equivalent, form here and in the following claims is meant alternate up, forward, down, and forward gliding movements of the legs which result in alternate lift and ground rolling contact of vehicle left and right member wheels. The term, and its equivalents, is also intended to encompass all other leg movements employed by skaters such as turning movements, movements utilized when coasting with all wheels on the ground, etc.

While the vehicle of this invention has been described by detailed reference to the specific embodiment shown in the drawing, there are, of course, many other embodiments within the scope of my invention differing numerously in noncritical features, materials of construction, etc., therefrom. Some of these alternative featural variants of the pictured embodiment of my invention have been mentioned above, and others will be suggested to those skilled in the art by the present teachings. Further examples, by way of illustration, of variant forms of my vehicle falling well within the scope of my invention are those with wheel assemblies differing noncritically from that shown in the drawing (such as, for example, those incorporating the use of more than one wheel on each left and right member); those embodying a toe captivating arrangement dissimilar to the footgrip combination of the drawing (such as, for example, a one-piece toe socket, integral with or fastened by any convenient means to the footrest); vehicles without the height adjusting feature described above (or without any height adjusting feature); vehicles with one-piece, rather than two-piece left and right members; vehicles with directly telescoping upper and lower parts or other incorporated means of fastening upper and lower parts together; etc.

In view of the many theoretically possible embodiments of my new vehicle, it is finally emphasized that all such which maintain a structural character consistent with the integrity of my invention as taught herein fall within the scope of the invention so long as they are encompassed by the claims following hereinafter.

I claim:

1. A rider-propelled vehicle adapted to be operated by a rider in standing position and comprising a pair of members, one of which is adapted for left arm, hand and foot use and the other for right arm, hand and foot use by said rider, each member, in turn, comprising:

- (a) wheel means adapted for ground rolling contact purposes;
- (b) mounting means for said wheel means adapted to receive the latter in rotatable relationship;
- (c) footrest means adapted to support one foot of said rider above ground level while he is operating said vehicle;

- (d) handle bar means adapted and positioned for grasp by one hand of said rider while he is operating said vehicle in standing position;
- (e) arm support means adapted to support one arm of said rider while he is operating said vehicle in standing position with the hand of that arm grasping said handle bar means; and
- (f) means interconnecting and supporting the aforesaid means in properly spaced apart and oriented positional status;
- (g) whereby the vehicle is operable by a rider standing with each foot on the footrest means of a separate one of said pair of members, each hand grasping a handle bar of a separate one of said pair of members, each forearm supported by the arm support means of a separate one of said pair of members, and propelling himself on the vehicle by leg movements somewhat like those of a skater.

2. The vehicle of claim 1 in which the wheel means comprises a single wheel having a rim with a resilient tire mounted thereon.

3. The vehicle of claim 1 in which the wheel means comprises a single wheel having a rim with a resilient tire mounted thereon, and the footrest means is positioned directly over and so oriented relative to the roll direction of said wheel that the foot of a rider operating the vehicle and positioned on said footrest is longitudinally aligned with said roll direction.

4. The vehicle of claim 1 in which said arm support means comprises an elongated rigid part and an upright arm grip member fixedly secured thereto, said arm grip member having upstanding side walls and being so elevated and oriented as to cradle between said side walls the forearm of said rider when he is operating said vehicle, said elongated rigid part being so positionally oriented as to substantially parallelly underlie said forearm of said rider when it is so cradled in said arm grip member.

5. A rider-propelled vehicle adapted to be operated by a rider in standing position and comprising a pair of members, one of which is adapted for left arm, hand and foot use and the other for right arm, hand and foot use by said rider, each member, in turn, comprising:

- (a) a wheel adapted for ground rolling contact purposes having a rim with a resilient tire mounted thereon;
- (b) mounting means for said wheel adapted to receive it in rotatable relationship;
- (c) footrest means adapted to support one foot of said rider while he is operating said vehicle, said footrest means being positioned directly over said wheel and so oriented relative to its roll direction that the foot of a rider operating the vehicle and positioned on said footrest is longitudinally oriented in said roll direction;
- (d) a handle bar adapted and positioned for grasp by one hand of said rider while he is operating said vehicle in standing position;
- (e) arm support means adapted to support one arm of said rider while he is operating said vehicle in standing position with the hand of that arm grasping said handle bar, comprising an elongated rigid part and an upright arm grip member fixedly secured thereto, said arm grip member having upstanding side walls and being so elevated and oriented as to cradle between said side walls the forearm of said rider when he is operating said vehicle, said elongated rigid part being so positionally oriented as to substantially parallelly underlie said forearm of said rider when it is so cradled in said arm grip member;
- (f) means interconnecting and supporting the above-enumerated elements in properly spaced apart and oriented positional status;
- (g) whereby the vehicle is operable by a rider standing with each foot on the footrest means of a sepa-

rate one of said pair of members, each hand grasping a handle bar of a separate one of said pair of members, each forearm supported by the arm support means of a separate one of said pair of members, and propelling himself on the vehicle by leg movements somewhat like those of a skater. 5

6. The vehicle of claim 5 in which the interconnecting and supporting means of subparagraph (f) comprises:

- (a) the major portion of an elongated, substantially rigid frame with lower end connective capacity for receiving said mounting means for said wheel in wheel flanking and supportive relationship; 10
- (b) the wheel flanking relationship between frame and wheel being such that the former is connected with the wheel mounting means inboard of the mounted wheel; 15
- (c) said frame extending substantially vertically upwardly from its lower end and then outwardly over said wheel in substantially axially parallel relationship thereto; 20
- (d) said frame thereafter bending to extend substantially vertically upwardly, then to extend forwardly and upwardly, then to extend substantially vertically upwardly again; 25
- (e) said frame then curving sharply backwardly, downwardly and outwardly from the rider's position and thereafter extending for a sufficient distance to serve as said handle bar;
- (f) said frame then curving, in substantially the same vertical plane, to extend rearwardly and slightly upwardly a sufficient distance to form said elongated rigid part of said arm support means. 30

7. The vehicle of claim 6 in which said elongated, substantially rigid frame is of metallic, substantially tubular construction. 35

8. The vehicle of claim 6 in which said elongated, substantially rigid frame is of light weight metal construction.

9. The vehicle of claim 6 in which the elongated, substantially rigid frame is of metallic, substantially tubular construction and comprises separable upper and lower parts and accessory interlocking means whereby they can be locked together to serve as a single frame unit. 40

10. The vehicle of claim 6 in which said footrest means comprises a flat, elongated, plate-like member fixedly secured atop that part of said frame extending outwardly over said wheel in substantially axially parallel relationship thereto; said plate-like member being oriented in longitudinal alignment with the roll direction of said wheel. 45

11. A rider-propelled vehicle adapted to be operated by a rider in standing position and comprising a pair of members, one of which is adapted for left arm, hand and foot use and the other for right arm, hand and foot use by said rider, each member, in turn, comprising: 50

- (a) a wheel adapted for ground rolling contact purposes having a rim with a resilient tire mounted thereon;
- (b) mounting means for said wheel adapted to receive it in rotatable relationship;
- (c) footrest means adapted to support one foot of said rider while he is operating said vehicle, said footrest means comprising a flat, elongated plate-like member and being positioned directly over said wheel and so oriented relative to its roll direction that the foot of a rider operating the vehicle and positioned on said footrest is longitudinally oriented in said roll direction; 55
- (d) a handle bar adapted and positioned for grasp by one hand of said rider while he is operating said vehicle in standing position;
- (e) arm support means adapted to support one arm of said rider while he is operating said vehicle in standing position with the hand of that arm grasping said handlebar, comprising an elongated rigid part and an upright arm grip member fixedly secured thereto, 75

said arm grip member having upstanding side walls and being so elevated and oriented as to cradle between said side walls the forearm of said rider when he is operating said vehicle, said elongated rigid part being so positionally oriented as to substantially parallelly underlie said forearm of said rider when it is so cradled in said arm grip member;

- (f) means interconnecting and supporting the above-enumerated elements in properly spaced apart and oriented positional status comprising the major portion of an elongated, metallic, substantially tubular and substantially rigid frame having separable upper and lower parts and accessory interlocking means whereby they can be locked together to serve as a single frame unit, said frame having lower end connective capacity for receiving said mounting means for said wheel in wheel flanking and supportive relationship;
- (g) the wheel flanking relationship between frame and wheel being such that the former is connected with the wheel mounting means inboard of the mounted wheel;
- (h) said frame extending substantially vertically upwardly from its lower end and then outwardly over said wheel in substantially axially parallel relationship thereto;
- (i) said frame thereafter bending to extend substantially vertically upwardly, then to extend forwardly and upwardly, then to extend substantially vertically upwardly again;
- (j) said frame then curving sharply backwardly, downwardly and outwardly from the rider's position and thereafter extending for a sufficient distance to serve as said handle bar;
- (k) said frame then curving in substantially the same vertical plane, to extend rearwardly and slightly upwardly a sufficient distance to form said elongated rigid part of said arm support means;
- (l) said footrest means being fixedly secured atop that part of said frame extending outwardly over said wheel in substantially axially parallel relationship thereto;
- (m) toe socket means adapted to protectively receive a front part of the foot of a rider operating the vehicle when said foot is positioned on said footrest means, said toe socket means cooperatively associated with said footrest means;
- (n) whereby the vehicle is operable by a rider standing with each foot on the footrest means of a separate one of said pair of members, each hand grasping a handle bar of a separate one of said pair of members, each forearm supported by the arm support means of a separate one of said pair of members, and propelling himself on the vehicle by leg movements somewhat like those of a skater.

12. The vehicle of claim 11 in which the accessory interlocking means for the separable upper and lower parts of the substantially rigid frame are adaptable for locking said parts together in varying positional combinations whereby the frame length, and, in turn, the vehicle height, is adjustable to suit the size of the vehicle rider. 60

13. The vehicle of claim 11 in which the plate-like footrest member is longitudinally slotted and the toe socket means cooperatively associated therewith comprises two metallic footgrip members, each of which has a flat strap-like first portion and a second portion rising therefrom in the shape of an incomplete arch, and accessory fastening hardware; 65

- (a) said footgrip members being so sized and configured as to underlyingly fit with their flat portions overlapping, against said plate-like footrest member with their incomplete arch portions flanking rising from opposite sides of said footrest member in a common arcuate pattern to form a receptive socket for the front part of the foot of a vehicle rider;

- (b) the flat strap-like first portions of said footgrip members being characterized by the presence of longitudinal slots so positioned as to partially overlap when said strap-like portions are fitted in underlying relationship with said plate-like footrest member in the above-indicated manner, and the slotted area of the footrest member being so located as to cross the overlapping portions of the slots in said footgrip members when they are thus underlying fitted to said footrest member;
- (c) said accessory fastening hardware comprising a screw adapted to pass through the superimposed slot areas in the footrest member and flat portions of said footgrips, when those parts are assembled as described above, and cooperating nut means for 15 tightening and loosening of said screw;
- (d) whereby the footrest-toe socket assembly is adjustable for the rider's foot length by longitudinal movement of the footgrips along the footrest member by movement of the loosened screw in the longitudinally slotted area of that member, and for the rider's foot width by lateral movement of said footgrip members, relative to the position of said footrest member, along their slot axes with the screw loosened but captive in said axes.

14. The vehicle of claim 13 in which the plate-like footrest member is so longitudinally slotted as to permit assembly of said footgrip members on its either end, whereby the footrest member-toe socket assembly, and

the separable lower part of said substantially rigid frame to which the footrest member is fixedly secured, is adjustable for interchangeable use as a part of either of said pair of members of said vehicle.

5 15. The vehicle of claim 11 in which the upstanding side walls of the upright arm grip member of the arm support means curve toward each other to thereby provide clamping, in addition to cradling, means for the forearm of said rider when he is operating said vehicle.

16. The vehicle of claim 11 in which said substantially rigid frame is of substantially light weight metal construction.

17. The vehicle of claim 11 in which said substantially rigid frame is of substantially aluminum construction.
